ANTICONDENSATION PANEL FOR VEHICLE
WINDOWS OR THE LIKE

Salomon Zell, 284 E. Park Drive, Blackpool,
Lancashire, England

Filed May 4, 1965, Ser. No. 85,092

Term of patent 14 years

(Cl. D14—27)

FIG.1

FIG.3

FIG.4

FIG.2

FIG. 1 is a front perspective view of an anticondensation panel for vehicle windows or the like and showing my new design;

FIG. 2 is a rear view in elevation of the panel shown in FIG. 1, and

FIGS. 3 and 4 are enlarged fragmentary cross-sectional views taken on lines 3—3 and 4—4, respectively, of FIG. 2.

I claim:

The ornamental design for an anticondensation panel for vehicle windows or the like, as shown.
